INVENTOR

BY Victor J. Evans

ATTORNEY

P. J. Hickey

WITNESS:

UNITED STATES PATENT OFFICE.

HENDRIK CHRISTIAANSEN, OF MILWAUKEE, WISCONSIN.

DOOR LOCK.

Application filed January 14, 1924. Serial No. 686,200.

To all whom it may concern:

Be it known that I, HENDRIK CHRISTIAANSEN, a citizen of Holland, residing at Milwaukee, in the county of Milwaukee and State of Wisconsin, have invented new and useful Improvements in Door Locks, of which the following is a specification.

My present invention has reference to an improved door lock.

10 The object is the provision of a burglar-proof lock which cannot be operated from the exterior of a room or building even when the key has not been operated to lock the bolts.

15 To the attainment of the foregoing, the invention consists in the improvement as hereinafter described and definitely claimed.

In the drawings:—

Figure 1 is a fragmentary elevation looking toward the inner face of a door provided with the improvement, the knob spindle being in section.

Figure 2 is a similar view but showing the latching means in inoperative position.

25 Figure 3 is an approximately central longitudinal sectional view through the lock casing showing the bolts in locking position.

Figure 4 is a similar view showing the bolts retracted.

Figure 5 is a perspective view of the fixed element of the catch.

Figure 6 is a similar view of the slidable element of the catch.

35 Figure 7 is a similar view of the escutcheon plate for the slidable element of the catch.

Figure 8 is a detail sectional view through one of the bolts.

40 In the drawings, the numeral 1 designates the inner face of a hinged door. Let in the edge of the door there is the casing of my improved lock. The casing includes a central substantially rectangular body portion 2 having outer end extensions 3. Preferably the extensions 3 have their outer faces extended to provide lips 4 through which pass the securing means for holding the lock in the door.

50 In carrying out my invention, I make use of two bolts 5 and 6 respectively. These bolts are received in notches in a suitable keeper 50. The bolts have their active faces preferably beveled, as at 7, so that the same

can slide over the keeper plate and into the 55 openings therein when the door is closed.

The bolts 6 and 7 are provided with right angular extensions or tail portions 8 and 9 respectively. The tail portions 8 and 9 are directed toward each other in the casing and 60 have passed therethrough suitable pivot members 10 whereby the bolts are swingably sustained in the casing. Each bolt is contacted by a spring 11 for projecting the same through the opening in the face of 65 the lock casing.

The knob spindle 12 is mounted in suitable bearing openings in the sides of the casing and, of course, passes through escutcheon plates on the inner and outer faces of 70 the door. The spindle is substantially square in cross section and has secured thereon, by means 13, a throw element 14. The element 14 comprises an elongated member having both of its ends tapered, and 75 one of said ends, indicated by the numeral 15, underlies the tail 8 of the bolt 5. The opposite end of the throw member 14 is in contacting engagement with one of the beveled edges 16 of a tumbler or auxiliary throw 80 member for the bolt. This throw member 17 is pivoted in the casing, as at 18, and has a second beveled edge or face 19 that underlies the tail portion 9 of the bolt 6. From the foregoing, it will be apparent that 85 when the knob spindle is turned to the position illustrated in Figure 4, the tail 8 of the bolt 5 will be swung toward the outer face plate of the casing by the turning of the throw member 14, and the latter influences the 90 tumbler or throw member 17 to likewise swing the tail 8 of the bolt 6 in the same direction. Thus the bolts are retracted. The springs 11 return the bolts to locking position when pressure on the knob connected with the spindle 12 is released.

Suitably mounted in the casing there are preferably spring influenced tumblers 20 kerfed or notched to receive the bit end of a key so that the same can be moved, when 100 the key is turned, toward and to be raised upon their guides 21 to cause the end 15 to be received in notches 22 in the straight edges of the tumblers 20. The tumblers 20 are disposed below the keyhole openings 23 105 in the casing.

On the inner face of the door there is an escutcheon plate 24 of a particular construc-

tion. The spindle 12 passes through a suitable bearing opening in the escutcheon 24, and fixed on the said spindle and disposed in close relation to the escutcheon 24, there is an approximately semi-circular plate 25. The plate has its upper and straight edge formed with notches 26-26, adjacent to its sides or edges, providing therebetween a central lug 27 and end lugs 28. The central lug may be and preferably is of a greater length than the end lugs 28 and is also wider, and through the said central lug 27, the spindle 12 passes. Suitable means is employed for holding the plate 25 on the spindle. The plate 25 provides the fixed element of the latch for the door.

The slideable element of the latch is also in the nature of a plate semi-circular in plan, the said plate having its lower straight edges provided with a pair of spaced fingers 29 designed to be received in the notches 26, to receive therebetween the lug 27 and to be arranged in contacting engagement with the lugs 28 of the plate 25. The slideable catch member 29 has an outer operating knob 30 and an inwardly extending headed lug 31. The lug 31 is received in a vertically disposed elongated slot 32 in the escutcheon 24. The lug 31 has its shank preferably square in cross section to contact with the side walls provided by the slot 32. The escutcheon plate 25 is provided with a rounded opening 33 which communicates with the upper portion of the slot and provides an extension therefor. The lower wall provided by the opening 33 is substantially straight and is designed to receive and hold therein the lug 31 when the movable latch member 29 is slid to inoperative position. The head of the lug 31 at all times holds the latch element 29 against the outer face of the escutcheon plate 24.

When the latch elements 29 and 25 are in interengagement, it will be seen that the knob 12 cannot be turned, and thus the opening of the door from the outside thereof will be positively prevented. Even when the tumblers engage the throw member 15, after the operation of the key, the lock cannot be picked, because the latching means will positively prevent the turning of the knob spindle 12 and unless the said spindle

is turned the throw member 14 will prevent the throwing of the bolts to unlocking position.

55

Having described the invention, I claim:

1. In a lock, a casing, bolts movable through the face thereof having inner angle ends which are pivoted in the casing, a spring for influencing the bolts to locking position, a knob spindle journaled in the casing, a throw element fixed thereon having opposite pointed ends, one of which underlying the angle extension of one of the bolts, key operated tumblers movable in the casing to engage one end of the throw member, a second throw member pivoted in the casing having opposed angle faces, one of which is in contacting engagement with the first mentioned throw member and the other in engagement with the extension of the second bolt, a fixed catch member on the knob spindle, a slideable catch member for cooperation therewith, guide means for the slideable catch member, and means for sustaining the said second catch member out of engagement with the fixed catch member.

2. The combination with a lock having spring influenced bolts, a knob spindle and means operated by the turning thereof for throwing the bolts to unlocking position, of a catch member fixed on the spindle and comprising an approximately semi-circular plate whose straight edge is notched adjacent to the sides thereof to provide a central and end lugs, and the knob spindle passing through the central lug, an escutcheon plate through which the knob spindle also passes having an elongated slot terminating in a rounded downturned extension, a slideable latch element comprising a plate having spaced lugs to be received in the notches of the first mentioned catch member, an operating knob on the outer face of the last mentioned catch member, and a squared headed shank on the inner face thereof received in the slot of the escutcheon plate and movable into the angle branch thereof when the last mentioned catch member is to be sustained out of engagement with the first mentioned catch member.

In testimony whereof I affix my signature.

HENDRIK CHRISTIAANSEN.
